United States Patent Office.

JAMES WOODS ROGAN, OF MEMPHIS, TENNESSEE.

Letters Patent No. 99,239, dated January 25, 1870.

IMPROVEMENT IN COTTON-BALE TIES.

The Schedule referred to in these Letters Patent and making part of the same.

To all whom it may concern:

Be it known that I, JAMES WOODS ROGAN, of Memphis, in the county of Shelby, and State of Tennessee, have invented a new and useful Improvement in Bale-Tie; and I do hereby declare that the following is a full, clear, and exact description thereof, which will enable others skilled in the art to make and use the same, reference being had to the accompanying drawing, forming part of this specification.

This invention relates to a new and useful improvement in ties for baling cotton, and to be used for all baling-purposes for which they are adapted, and it has special reference to the means of passing one end of the band or hoop into the buckle, and the construction of the tongue of the latter, hereinafter described.

In the accompanying drawing—

Figure 1 represents a top or plan view.

Figure 2 is an edge view.

Similar letters of reference indicate corresponding parts.

A is a buckle, having a slot, B, at one end, to which one end, C, of the band, is attached, by hooking it over the bar D, of the buckle, as seen in fig. 2.

E is the tongue of the buckle, having a neck, F, and two square shoulders, g g.

The other end of the band, C', is provided with orifices H H, of key-hole form, through which the tongue is made to pass, as seen in the drawing.

The end C of the band or hoop being attached to the bar D, as seen in fig. 1, the other end, C', is brought around the bale, and passed under the bar I, of the buckle. The end of the tongue E is passed through the broad portion of the orifice H.

The expansion of the bale draws the narrow end of the orifice H in contact with the shoulders g g, of the tongue, and the fastening is complete.

J represents a break in the side of the buckle, through which the band or hoop may be passed into the buckle, when it is found more convenient to make the connection in that manner. It will be seen that the strain is on the other portion of the buckle. The form of the tie is so plainly shown in the drawing, that further description is deemed unnecessary.

Having thus described my invention, I claim as new, and desire to secure by Letters Patent—

The buckle A, provided with the break J, and with the tongue E, having shoulders g, in combination with the hoops C and C', the latter having a T-shaped slot or aperture, all arranged as set forth and shown.

JAMES WOODS ROGAN.
